Patented Aug. 10, 1920.

Application filed February 2, 1920. Serial No. 355,778. Term of patent 14 years.

To all whom it may concern:

Be it known that I, REUBEN B. BENJAMIN, a citizen of the United States, residing at Chicago, in the county of Cook and State of Illinois, have invented a new, original, and ornamental Design for a Plug-Cluster, of which the following is a specification, reference being had to the accompanying drawing, forming a part thereof.

The figure is a side elevation of a swivel shell plug cluster.

In order to give a clearer understanding of the construction than could be obtained from the drawing, it is stated that the part of the fixture having the stippled surface may be porcelain or other insulating material.

I claim:

The ornamental design for a plug cluster, substantially as shown.
